ATTORNEY'S

UNITED STATES PATENT OFFICE

WILLIAM S. ROSS, OF PIQUA, OHIO, ASSIGNOR TO THE FAVORITE STOVE AND RANGE COMPANY, OF PIQUA, OHIO, A CORPORATION OF OHIO

ARTICULATED TOP COVER FOR GAS RANGES

Application filed December 31, 1930. Serial No. 505,797.

This invention relates to improvements in tops or covers for gas ranges, and has for its object to provide a cover pivoted to the back part of the stove and formed into sections pivoted to each other.

It is also an object of this invention to provide, in connection with a stove or range of the type here shown, means for supporting a top or cover in an elevated position so that the stove may be used without the cover, and at the same time the cover will be supported out of the way.

It is also an object of this invention to provide, in connection with a range having a shelf thereon, a downwardly extending forward lip for engaging a part of the cover for holding it in frictional engagement when not in use.

I also comprehend within my invention the location of section 9, slightly above the horizontal plane running through the hinge when the cover is in inoperative position, so the tendency of the cover to return to its operative position will cause a frictional engagement between the nose 13 and the lip 5, which engagement is assisted by the spring 12. For instance, when the cover is in inoperative position it is located on the recessed back and recessed hood; and the joint of the articulated cover is below the point of engagement of the edge of the cover with the interior of the hood so that the cover tends to remain in inoperative position.

Referring to the drawings:

Figure 1 is a front elevation of a range or stove to which the present cover is attached.

Figure 2 is a section on the line 2-2 of Figure 1.

Figure 3 is an enlarged view of the hinge connection between the rear side of the cover and the rear part of the stove.

Figure 4 is an enlarged view showing the manner in which the two parts of the cover are hinged together.

In Figure 1 there is shown a range or stove as a whole, to which the present invention is adapted to be attached. This stove is indicated by the numeral 1, and has on one side thereof the ordinary baking oven 2. The top of the frame of the stove is indicated by

the numeral 3. This part of the stove is such as is usually found in connection with gas stoves and ranges, and has the usual upwardly extending back part 4 and a forwardly extending shelf 4' with a downwardly extending lip 5.

The cover constituting the subject-matter of this invention is pivoted by means of hinge 7 to the rear part of the stove adjacent the back 4. This cover consists of two parts, a back part 6 pivoted to the back of the stove by the hinge 7. The front edge of this back part or section is bent in the form of a loop 8. The front part or section of the cover is indicated by the numeral 9, and has along its back edge a loop 10 which is adjacent the loop 8. The two sections are joined together along the loops 8 and 10 by means of hinges 11, one strap of the hinge being attached to the loop 8, the other strap to the loop 10.

To the loop 8 is also attached a spring 12. The front of the section 9 is bent down, as indicated by the numeral 13, and rests on the front part of the stove top 3, as shown in Figure 2. In Figure 2 the stove top is shown in lower position for the purpose of use. In dotted line this stove top is shown in partly folded and out-of-use position.

When the cover is elevated, as shown in dotted lines in this figure, the rear portion of the cover assumes a vertical position adjacent the back 4, whereas the portion 9 assumes a position slightly out of horizontal with the front end, engaging with the lip 5. By means of the spring 12 and the frictional engagement between the lip 5 and the front end of the portion 9, the cover is held in elevated position. The spring 12 tends to hold the part 9 up so that it engages the lip 5. The two actions tend to hold the cover in elevated position so that the top of the stove is free from the cover and may be used without interruption or interference by the cover. On the front edge of the portion 9 of the cover is a hand knob 14. This hand knob may be seized by the hand of the operator for moving the cover either to elevated position or from elevated position back to horizontal position on the top of the stove.

I desire to comprehend within my inven-

tion such modifications as may be embraced within my claims and the scope of my invention.

Having thus fully described my invention, what I claim as new and desire to secure by Letters Patent, is:

1. A cover for a gas range consisting of a plate member formed of sections hinged to each other and hinged to the top of the range, and means on one of said sections to hold the other section in a substantially horizontal position when said first section is in a vertical position.

2. A cover for gas ranges consisting of a plate member formed of sections hinged to each other and hinged to the top of the range, and spring means on one section to hold the other section in a substantially horizontal position when the first section is in a vertical position.

3. A cover for gas ranges consisting of a plate member formed of sections hinged to each other and hinged to the top of the range, and a looped spring extending from one section and adapted to engage and hold the other section in a substantially horizontal position when the first section is in a vertical position.

4. In a gas range cover, in combination with a shelf on the range, a plate member formed of sections hinged to each other, a hinge connection between the plate member and the top of the range whereby the plate member may be elevated with one portion in a vertical position and the other portion in a substantially horizontal position, and means on the shelf to engage the horizontal portion to hold the plate member elevated.

5. In a gas range cover, in combination with a shelf on the range, a plate member formed of sections hinged to each other, a hinge connection between the plate member and the top of the range whereby the plate member may be elevated with one portion in a vertical position and the other in a substantially horizontal position, means on the shelf to engage the horizontal portion to hold the plate member elevated, and means on the plate member tending to hold the horizontal portion in engagement with the shelf.

6. In a gas range cover, in combination with a shelf on the range, a plate member formed of sections hinged to each other, a hinge connection between the plate member and the top of the range whereby the plate member may be elevated with one portion in a vertical position and the other in a substantially horizontal position, means on the shelf to engage the horizontal portion to hold the plate member elevated, and spring means on the plate member tending to hold the horizontal portion in engagement with the shelf.

7. In a gas range cover, in combination with a shelf on the range, a plate member

formed of sections hinged to each other, a hinge connection between the plate member and the top of the range whereby the plate member may be elevated with one portion in a vertical position and the other portion in a substantially horizontal position, means on the shelf to engage the horizontal portion to hold the plate member elevated, and a spring on the vertical portion engaging the horizontal portion and tending to hold the horizontal portion in engagement with the shelf.

8. In a stove, an articulated cover, a hood having a depending margin, said cover being arranged when in inoperative position for one part thereof to assume a vertical position and the other part thereof to assume a position slightly above a horizontal plane with its free edge engaging said depending hood margin on the interior thereof, whereby the position of the last-mentioned section of the articulated cover being slightly above the horizontal plane will tend to retain the cover in its inoperative position.

9. In a stove, an articulated cover, a hood having a depending margin, said cover being arranged when in inoperative position for one part thereof to assume a vertical position and the other part thereof to assume a position slightly above a horizontal plane with its free edge engaging said depending hood margin on the interior thereof, whereby the position of the last-mentioned section of the articulated cover being slightly above the horizontal plane will tend to retain the cover in its inoperative position, and yielding means associated with the articulated joint of the cover cooperating in maintaining it in inoperative position and in frictional engagement with the depending lip.

10. In a stove, a horizontally disposed burner portion, an articulated cover therefor hinged at the rear thereof to the burner portion, a recessed vertical back, a recessed horizontally disposed hood having a downwardly turned margin, said cover being so arranged that when in inoperative position the burner portion thereof is received in said back and the horizontal portion thereof is received within said hood and in engagement with said margin.

11. In a stove, a horizontally disposed burner portion, an articulated cover therefor hinged at the rear thereof to the burner portion, a recessed vertical back, a recessed horizontally disposed hood, said cover being so arranged that when in inoperative position the burner portion thereof is received in said back and the horizontal portion thereof is received within said hood, and yielding means associated with said articulated cover for maintaining the sections thereof in said position.

12. In a stove, a horizontally disposed burner portion, an articulated cover therefor hinged at the rear thereof to the burner por-

- tion, a recessed vertical back, a recessed horizontally disposed hood, said cover being so arranged that when in inoperative position the burner portion thereof is received in said back and the horizontal portion thereof is received within said hood, and means on the interior of said hood and the exterior of said cover for frictional engagement with each other.
- 10 13. In a stove, a horizontally disposed burner portion, an articulated cover therefor hinged at the rear thereof to the burner portion, a recessed vertical back, a recessed horizontally disposed hood, said cover being so arranged that when in inoperative position the burner portion thereof is received in said back and the horizontal portion thereof is received within said hood, means on the interior of said hood and the exterior of said cover for frictional engagement with each other, and a pivoted joint for said articulated cover arranged below the point of engagement of the edge of the cover with the interior of the hood when the cover is in inoperative position.
